UNITED STATES PATENT OFFICE

2,638,100

COMB

John J. Lazicki, New York, N. Y.

Application December 3, 1949, Serial No. 130,898

1 Claim. (Cl. 132—15)

1

This invention relates to a comb, and more particularly to a folding comb for dressing hair in which the several parts thereof may be separated so as to permit the thorough washing and cleaning of the teeth.

Prior to this invention, combs were devised consisting of hinged separable parts each having spaced teeth thereon, which teeth were so spaced, on each of the parts, as to be disposed between adjacent pairs of teeth on the other of the parts when the parts were in closed confronting relationship to provide a single row of closely spaced teeth. These prior combs, however, were formed of dissimilar parts or sections in order to obtain the interlocking relationship between the teeth on one part and the teeth on the other part. Therefore, it was necessary to provide at least two dies for the purpose of forming the required sections or parts for the foldable comb.

An object of this invention is to provide a foldable comb consisting of a pair of sections, or comb members, formed with interlocking teeth.

Another object of this invention is to provide a construction for a foldable comb having interlocking teeth, in which the entire comb can be formed from a single mold or die.

A further object of this invention is to provide a comb composed of a pair of hinged sections, each having a plurality of relatively widely spaced apart teeth thereon so arranged as to engage between the teeth of the other section when the sections are in operative confronting position.

Finally, an object of this invention is to provide a construction for a foldable, multi-section comb which is simple and inexpensive to form and assemble.

In the following description and accompanying drawing preferred embodiments of the invention are set forth, however, it is to be understood that modifications and changes may be resorted to without departing from the spirit of the invention as defined in the appended claim.

In the drawing:

Figure 1 is a side elevation of a preferred embodiment of the invention showing the several parts of the comb in operative position.

Figure 2 is a top view of the comb illustrated in Figure 1, with the sections in operative position.

Figure 3 is an end view of the comb illustrated in Figure 1, with the sections in operative position.

Figure 4 is a side elevation of the comb illustrated in Figure 1, with the sections disposed in extended or cleaning position.

2

Figure 5 is an end view of the comb illustrated in Figure 4, with the sections separated, and with one of the sections shown in broken lines in an intermediate position.

Figure 6 is a side elevation of a blank from which a modified form of this invention is produced.

Figure 7 is a top view of the blank illustrated in Figure 6, and

Figure 8 is a side elevation of an assembled comb formed from the blank shown in Figures 6 and 7.

Referring to the drawing, and initially to Figures 1 through 5 thereof, a comb constructed according to a preferred embodiment of this invention, and generally indicated by the reference numeral 10, is there illustrated. The comb 10 is composed of a pair of identical comb sections 11 and 12. Each comb section consists of a spine or back member 13, having a relatively thick tooth 14 extending at right angles relative to the length of the spine or back member 13 and at one end thereof. A plurality of spaced teeth extending substantially parallel to each other are formed integral with the spine or back member 13. As seen in Figures 3 and 5, the teeth 14 and 15 are off-set laterally relative to the spine or back member 13 and form ribs at their upper portions on the spine which extend to the top edge of the latter. The last of the series of teeth indicated by the numeral 16 is spaced inwardly from the adjacent end 17 of the spine 13 a distance substantially equal to the spacing between adjacent teeth. A pair of hinge portions 18 and 19 are formed integrally with the top edge of the spine 13 of each comb section. The distance *a* between the outer edge of the hinge portion 18 and the adjacent end of the spine 13 is equal to the difference between the distance *b*, which is the distance from the outer edge of the hinge portions 19 to the edge or end of the spine 13 which is adjacent thereto, and the distance *c* which represents the width of the leaf portion.

In assembling the comb sections 11 and 12 in order to form a comb 10, the sections 11 and 12 are disposed oppositely to one another so that the hinge portion 18 of one comb section engages the hinge portion 19 of the other comb section. Pivot pins 20 are then extended through the registering hinge portions 18 and 19 in order to rockably secure the sections 11 and 12 to each other. As seen in Figure 4, the thickened tooth 14 of the section 12 will be disposed in line with the portion of the spine 13 of the section 11 which extends beyond the last tooth 16. Similar-

ly the thickened tooth 14 of the section 11 will be aligned with the portion of the spine of the section 12 which extends beyond the latter's last tooth 16. The teeth 15 are so disposed along the length of the spines 13 of each of the sections 11 and 12 as to be disposed in alternating relationship. That is, when the sections 11 and 12 are pivoted together into the position illustrated in Figures 1, 2 and 3, the teeth 15 of the section 11 will lie between the teeth 15 of the section 12. This will provide a comb having relatively thick teeth on the opposite ends thereof, and a plurality of relatively closely spaced intermediate teeth 15. Since the two sections 11 and 12 are identical in configuration, it is apparent that the entire comb may be formed with a single mold or die. If the comb is to be formed of a plastic or similar substance, the use of a single mold to form the two sections of the comb, will result in a considerable saving in the cost of manufacture. Further, the lateral off-set of the teeth 14, 15 and 16 with respect to the related spine 13 provides for the co-planar arrangement of the teeth on the two comb sections when the latter are swung together (Fig. 3), and the upward continuations of the teeth to form ribs on the spines 13 ensure adequate strength for the teeth without increasing the bulk of the comb.

Referring to Figures 6, 7 and 8, a modification of this invention is there disclosed. In Figures 6 and 7, a blank is illustrated from which the completed assembled comb in Figure 8 may be formed. The blank A includes an elongated spine forming portion 21 having an indentation or reduced area cross section 22 extending across the middle thereof. A relatively thick tooth 23 is formed integral with one end of the spine forming portion 21 and includes a hinge section 24. A complementary hinge section 25 is formed upon the opposite end 26 of the spine forming portion 21. Immediately to one side of the groove or reduced area section 22, a second thickened tooth 27 extends from the spine 21. The tooth 27 is disposed on the side of the groove 22 towards the other thickened tooth 23. A plurality of equally spaced apart parallel teeth 28 are formed upon the spine 21. The first tooth 29 of the series of teeth 28 is spaced inwardly from the center line of the hinge section 25 a distance d which is equal to the distance from the center line of the hinge section 24 to the center of the space 30 provided between the teeth 23 and the tooth 31. As in the first described embodiment, the teeth 23, 27, 28, 29 and 30 are off-set laterally from the spine 21 and continue to the top edge of the latter to form reinforcing ribs. The entire blank A is then formed in a single die or mold, and after a suitable hardening period, is cut at the point 22. The hinge sections 24 and 25 are then joined by the hinge pin 32 and the pair of comb sections thereby provided are swung into confronting relationship as shown in Figure 8. One of the sections so provided will have the thickened teeth 23 and 27 disposed at the opposite ends thereof, and the teeth 28 formed upon one of the sections will be disposed between

the teeth 28 of the other section. A U-shaped spring clamp 33 engages over the ends of the sections furthest removed from the hinged sections 24 and 25, for maintaining the pair of sections in the confronting position illustrated by Figure 8.

When it is desired to clean the comb formed in either of the embodiments of this invention described above, the pair of sections are pivoted away from each other and it is a simple matter to thoroughly clean between the relatively widely spaced apart teeth 15 and 28. When the sections are folded together, the teeth, which engage between each other, will be relatively closely disposed thus providing an effective combing implement.

In each of the embodiments described above and illustrated in the accompanying drawing, a single mold is all that is required in forming the two sections of the comb structure.

From the foregoing it is evident that there has been provided herein a hinged double comb having a pair of comb sections, each of the sections including an elongated spine member, a plurality of spaced parallel teeth formed integral with the spine member, the teeth being off-set laterally relative to said spine member and having the top ends thereof coextensive with the top edge of the spine member, hinge means being provided which connect the comb sections together at the spine members thereof, the teeth of one of the comb sections being so disposed therealong as to engage between the teeth of the other of the comb sections when the comb sections are in an operative position.

Having thus described the various modifications of this invention, what is claimed is:

A hinged double comb comprising a pair of comb sections, each of said sections including an elongated spine member, a plurality of spaced parallel teeth formed integral with said spine member, said teeth being off-set laterally relative to said spine member and having the top ends thereof coextensive with the top edge of said spine member, and hinge means connecting said comb sections together at said spine members thereof, the teeth on one of said comb sections being so disposed therealong as to engage between the teeth of the other of said comb sections when said comb sections are in an operative position.

JOHN J. LAZICKI.
